UNITED STATES PATENT OFFICE.

CHARLES L. EMMONS, OF CRANFORD, NEW JERSEY, ASSIGNOR TO THE AEOLIAN COMPANY, A CORPORATION OF CONNECTICUT.

TRACKING DEVICE.

1,387,371.

Specification of Letters Patent.

Patented Aug. 9, 1921.

Application filed October 21, 1920. Serial No. 418,431.

To all whom it may concern:

Be it known that I, CHARLES L. EMMONS, a citizen of the United States, residing at Cranford, New Jersey, have invented certain 5 new and useful Improvements in Tracking Devices, of which the following is a specification.

My present invention relates to improvements in tracking devices for use in player-pianos and the like and resides particularly in the means for adjusting the tracking device bodily to give it a proper factory adjustment relative to the tracker-bar, music-roll, etc.; and also resides in the further 15 means, intended for manipulation by the user of the instrument, to adjust the tracking device to operate with music-sheets of different widths.

My present device has these and other features and advantages which will be apparent to those skilled in the art from an understanding of the following description in connection with the drawings.

In the drawings, Figure 1 is a front elevation of the music-roll box portion of a player-piano embodying my tracking-device improvements; Fig. 2 is an enlarged plan view partly in horizontal section on the line 2—2 in Fig. 1, or on the same line in Fig. 3; Fig. 3 is an elevation partly in vertical section on the line 3—3 in Fig. 2; and Fig. 4 is an enlarged view of the tracker-bar and related parts as seen from the front of the instrument as in Fig. 1.

I will now describe the devices of the drawings illustrating only one of the possible embodiments of my invention, this, however, being the at present preferred embodiment thereof.

The illustrated player-piano parts comprise the following: 1 is the tracker-box; 2 the tracker-bar; 3 the take-up spool supported on the trunnions 4; and 5 is a music-roll spool and perforated music-sheet. Said 45 spool is removably supported as usual on the spindles 6 and 7.

8 is the usual pneumatic motor for unwinding and rewinding the music-sheet. 9 is the usual clutch-lever means for operating the usual clutch-sleeve 10, so that the motor 8 can be caused either to drive the take-up spool 3 to unwind and play the perforated music-sheet, or vice versa to drive the music-roll spool 5 to rewind the music-sheet upon 55 its spool after it has been played. The illus-

trated chain and sprocket mechanism and the gearing comprise the usual mechanism for accomplishing this and consequently need no detailed description.

11 is a tension spring connecting the left hand music-roll supporting-spindle with the side of the tracker-box so as to press the spindle yieldingly to the right and also to force the right handle spindle 7 yieldingly to the right when the music-roll spool 5 is 65 located between the spindles, thereby keeping the free end of said right hand spindle constantly against the face of the cam 12. This cam is part of the elbow-lever 13 pivotally supported at 14 on a fixed part or 70 frame.

15 and 16 are a pair of opposed pneumatics mounted on opposite sides of a stationarily supported board 17, a link 18 connecting the movable boards of said pneumatics.

Both pneumatics are normally on suction applied through the pipe 19, channel 20 in the stationary board and the bleeds 21—21. Other channels 22 and 23 in the stationary 80 board connect freely with the respective pneumatics 15 and 16 at their upper ends and with the tubes 24 and 25 at their lower ends. The other ends of these tubes 24 and 25 connect respectively with the elbow-shaped tubes or nipples 24^a and 25^a. (See Fig. 2).

The mouths of these nipples constitute ports appurtenant to tracker-bar and controlled respectively by the valves 26 and 27 90 to govern the admission of atmospheric air into the above described pneumatics 15 and 16, and thereby influence and control their operation.

These pneumatics communicate their motion to rock the above described cam-lever 13 by means of the rod-member 28—29 (Fig. 1), 29 being the usual turn-buckle and oppositely screw-threaded connection for accurately adjusting the length of the member 100 when setting up the device.

The above described nipples 25^a and 25^b form part of the horizontally extending blocks 30 and 31 (see plan view Fig. 2) supported by the leaf-springs 32 and 33 from 105 the sides of the tracker-box. Said blocks 30—31 are adjustably connected with each other by the rod 34 whose oppositely screw-threaded ends 34^a and 34^b engage correspondingly screw-threaded blocks or parts 110

35 and 36 having screw-threaded stems 35^a and 36^a respectively, which engage threaded openings in the respective blocks 30 and 31. But these stems are not screwed up hard 5 against any shoulder. On the contrary, they are purposely free to rotate in both directions so that the blocks 30 and 31 can freely swivel relatively to the head-parts 35 and 36 of the stems which as above described are 10 mounted on the oppositely screw-threaded ends of the rod 34.

37 is a knurled-head fixed on the right hand end of the rod 34 large enough in diameter to project through and below a 15 fore and aft slot in the lower board 38 of the casing of the tracker-bar. This permits the player of the instrument to rotate the knurled head by applying the finger to it on the under-side of the tracker-bar. Depending upon the direction of rotation given said 20 knurled-head,—the rod 34 will be correspondingly rotated and its oppositely screw-threaded ends will simultaneously and equally adjust the parts 35—36 either farther apart or nearer together. Further, the 25 blocks 30 and 31 supported as described on the stems of said parts 35—36 will receive the same adjustment and at the same time can swivel slightly as required by their attachment by the leaf-springs 32—33 to the 30 sides of the tracker-bar.

These leaf-springs 32 and 33 are tensioned so as to press the blocks 30 and 31 constantly toward each other and thereby take up any 35 lost motion or play in the described connections between said blocks and the rod 34.

Referring back now to the valves 26 and 27, these are supported respectively on the rear ends of the levers 39 and 40 centrally 40 pivoted at 39^a and 40^a to the blocks 30 and 31, with their front ends 39^b and 40^b projecting freely through special openings in the tracker-bar so as to be engaged by the two side-edges of the music-sheet traveling 45 across the tracker-bar between them. The usual light springs 41 and 42 normally keep or tend to keep the valves 26 and 27 lightly seated on the control ports.

The described manipulation of the knurled 50 head 37 to adjust at will the blocks 30 and 31 simultaneously and equally either nearer together or farther apart will, of course, impart the same adjustment to the aforesaid valve levers 39 and 40 carried by said blocks. 55 In other words, the player of the instrument by means of the knurled head 37 can very easily and quickly adjust the projecting ends 39^b and 40^b (Fig. 2) of the levers so that they both just touch the side-edges of the 60 given music-sheet; and can readily effect this same adjustment every time he plays a music-sheet which is wider or narrower than the previously played music-sheet.

I have purposely made the knurled head 65 37 project through a slot in the bottom as

distinguished from the top of the tracker-bar casing so as not to receive as much dust and so that its adjustment will not be so likely to be accidentally changed when dusting the instrument, etc.

70

The foregoing assumes that the mechanism supported by the leaf-springs 32—33 has previously received a factory adjustment so that it is centralized,—that is to say, symmetrically disposed relatively to the median line of travel of a normal music-sheet in normal tracking relationship to the tracker-bar.

This requires a delicate factory adjustment of the aforesaid mechanism as an entirety relatively to the tracker-bar, etc., to accomplish which I provide means as follows:—In the first place, I give greater tension to the leaf-spring 32 so that it tends to overpower 33 and force to the left in 85 Figs. 1 and 2 the entire mechanism supported by said springs. Secondly, I adjustably oppose this action of said stronger spring 32 by providing a screw 43 which projects through the left cheek of the tracker-box and abuts against the left hand end of the rod 90 34. By turning this screw, the mechanism, including the valve lever ends 39^b and 40^b, supported by the springs 32 and 34, can be adjusted into accurate symmetrical relationship relatively to the tracker-bar music-ducts, etc. This once accomplished, then it becomes possible for the player to adjust, as already described, said lever-ends 39^b and 40^b to music-sheets of different widths by operating 95 the knurled-head 37.

To prevent the screw 43 from unintentionally turning and putting the mechanism out of adjustment, I provide any suitable means such as a strong leaf-spring 44 pressing 105 frictionally against the head 43^a of the screw. Also preferably, I make the plate 45 of sole-leather or other gripping material through which the threaded end of the screw 43 is tapped.

Aside from the described adjustment features, the tracking-device works in the usual manner, viz:—As long as the music sheet remains in track, the pneumatics 15 and 16 are balanced in power and the parts are maintained in the relative positions shown in Fig. 1. As soon, however, as the traveling sheet begins to swerve out of track, it opens wider the valve (26 or 27) on that side, whose port thereupon allows relatively more atmospheric air into the connected pneumatic (15 or 16), weakening it and causing it to be overpowered by the other pneumatic, which in turn results in sliding the rod 28 and swinging the cam-lever 13 to adjust the cam 12 to adjust the music spool in the proper direction to restore the sheet back into track.

Of course, changes and modifications can be made in the foregoing embodiment of my 130

invention which will be obvious to those skilled in the art without departing from the essential nature and spirit thereof or of the following claims.

5. What I claim is:

1. In a tracking device for an automatic musical instrument, the combination of a unitary structure comprising the control ports of the tracking device together with 10 means for adjusting them equally and simultaneously nearer together or farther apart; and means for adjusting said unitary structure to centralize it in its operative position.
2. In a tracking device for an automatic 15 musical instrument, the combination of a unitary structure comprising the control ports of the tracking device together with means for adjusting them nearer together or farther apart; and means for adjusting 20 said unitary structure to centralize it in its operative position.
3. In a tracking device for an automatic musical instrument, the combination of a unitary structure comprising the control 25 ports of the tracking device together with a rotary rod having oppositely threaded ends having screw-connection with said ports for adjusting them nearer together or farther apart; and means for adjusting said 30 unitary structure to centralize it in its operative position.
4. In a tracking device for an automatic musical instrument, the combination of a unitary structure comprising the control

ports of the tracking device together with a 35 rotary rod having oppositely threaded ends having screw-connection with said ports for adjusting them nearer together or farther apart; a spring for pressing said unitary structure in one direction and means for adjusting said structure in the opposite direction against the tension of said spring.

5. In a tracking device for an automatic musical instrument, the combination of control-port parts spring-supported at the sides 45 of the tracker-box, one of said parts being spring-pressed more strongly than the other toward the opposite side of the tracker-box, a rotary rod having oppositely screw-threaded ends, nuts on said ends having swiveling 50 connection respectively with the control-port parts, and an adjusting screw acting on said rod in opposition to the aforesaid stronger spring.

6. In a tracking device for an automatic 55 musical instrument, the combination of control-port parts movably supported at the sides of the tracker-box, a rotary rod having oppositely screw-threaded ends, nuts on said ends having swiveling connection respectively with the control-port parts, and means for manually rotating said rod accessible 60 from the underside of the tracker-bar.

In testimony whereof, I have signed my name to this specification this 18th day of 65 October, 1920.

CHARLES L. EMMONS.
